UNITED STATES PATENT OFFICE

GUSTAVE M. FAUSER, OF ARDSLEY ON HUDSON, NEW YORK, ASSIGNOR TO ATKINSON, WADE & COMPANY, INC., OF NEW YORK, N. Y.

DESIGN FOR A TEXTILE FABRIC OR SIMILAR ARTICLE

Application filed March 31, 1931. Serial No. 39,310. Term of patent 3½ years.

To all whom it may concern:

Be it known that I, GUSTAVE M. FAUSER, a citizen of the United States, and resident of Ardsley on Hudson, in the county of Westchester and State of New York, have invented a new, original, and ornamental Design for Textile Fabrics or Similar Articles, identified as No. 3, and of which the following is a specification, reference being had to the accompanying drawing, forming part thereof.

The figure of the drawing is a plan view of a piece of textile fabric comprising the design unit.

I claim:

The ornamental design for a textile fabric or similar article, substantially as shown and described.

Signed at New York city in the county of New York and State of New York this 30 day of March A. D. 1931.

GUSTAVE M. FAUSER.
